UNITED STATES PATENT OFFICE.

ARTHUR J. CANFIELD, OF MONTREAL, QUEBEC, CANADA.

METHOD OF MAKING DRAFT-GEAR YOKES.

1,404,833.

Specification of Letters Patent. Patented Jan. 31, 1922.

Application filed April 20, 1920. Serial No. 375,303.

To all whom it may concern:

Be it known that I, ARTHUR J. CANFIELD, a citizen of the United States, and resident of the city of Montreal, in the Province of Quebec and Dominion of Canada, have invented certain new and useful Improvements in Methods of Making Draft-Gear Yokes, of which the following is a full, clear, and exact description.

10 This invention relates to an improved process or method for the manufacture of draft gear yokes and the object of the invention is to provide for the manufacture of seamless, one-piece yokes in an expeditious 15 and economical manner.

At the present time, yokes are for the most part manufactured by forging or welding two or more members together and it has been found that such yokes have a tendency 20 to failure at one or other of the welds.

According to the present invention the yoke is made in one piece. A suitable length 25 of seamless steel tubing of appropriate diameter and wall thickness is formed to the desired shape by a series of suitable forging and cutting operations.

In the drawings which illustrate the invention;—

30 Fig. 1 is a perspective view of a length of tube.

Figs. 2 to 4 inclusive are perspective views illustrating different stages of the manufacture.

35 Fig. 5 is a perspective view of the complete yoke.

Figs. 6 and 7 are fragmentary perspective views illustrating different methods of closing the inner end of the yoke.

40 Referring more particularly to the drawings, 11 designates a tubular body open at both ends and provided at a suitable stage in the manufacture with two opposite flat sides 12 and two intermediate opposite flat 45 edges or remaining sides 13. The body is of greater depth in a portion 16 at one end than in the remainder of the body and may, if desired, be also of greater width in this portion. The top and bottom 12 in the enlarged portion 14 are separated to form jaws 15 which are thickened at their tips, as at 50 16, and slotted as at 17 from the thickened portions for a suitable distance toward the opposite end. The two opposite sides of the body extend at the end opposite the jaws 55 beyond the remaining sides, as shown at 18,

and these extending portions 18 are connected together in any suitable manner as by means of rivets 19 to close the end of the body. The top and bottom of the body are 60 provided with openings 20 of suitable size for the introduction of draft gear springs:

The process of making the body may vary in details and in the order of its steps according to circumstances such as the particular design of the finished article, the quality of the material and the capabilities of the plant. For these reasons, the following description must not be regarded as 65 limitative but merely as descriptive of one 70 sequence of particular steps. Starting with a suitable length of seamless steel tubing.

75 forming a hollow body 11, the body is reduced by a forging or pressing operation to the form shown in Figure 2, that is, a hollow body rectangular in cross section and having a portion 14 toward one end of greater depth than the remainder of the body. The tubular body 11, which is the raw material supplied for the carrying out 80

of this process, may be either cylindrical as shown in Figure 1 or may be rectangular in cross section. If a cylindrical body is started with, the first operation will be a flattening one which will include the formation 85 of the large end portion 14, but, if the raw material is rectangular in cross section, the first operation will be merely one of forging to form the enlarged portion 14.

The edges of the body in the enlarged portion are now cut away, as indicated by dotted lines in Figure 2, the cutting being 90 effected either by shearing or burning away the metal with an oxyacetylene flame or welding arc. This forms separate jaws on 95 the top and bottom of the body, which in the next operation are drawn out to the tapering form shown in Figure 3. While the jaws are being drawn out, two opposite sides at the opposite end of the body may also be drawn out to project beyond the remaining sides, as shown at 18. This drawing out 100 may be effected in the top and bottom, as shown, or may be in the edges 13 if desired, as shown in Figure 7. The body is now 105 placed in suitable dies and the jaws 15 subjected to a swaging or upsetting operation, which gives them their final shape and at the same time thickens their extremities, forming the bosses 16. In this swaging operation, the jaws may also be spread apart 110 as will be seen by a comparison of Figures

3 and 4. It will be understood that this spreading is not essential but is merely a matter of design. The jaws are next slotted, as shown at 17, and the top and bottom of 5 the body provided with the openings 20. The slotting is preferably done in a punch press and the openings 20 may be formed in the same manner or by burning out the metal to be removed, as described in connection with the formation of the jaws. The 10 drawn out end portions 18 are now bent over the end of the body to close the same and connected together by rivets 19 or by any suitable form of weld. 15 While from the order of the steps in the foregoing description, it will appear that the end closing is the last step in the manufacture, it must be understood that this is not in any way essential, as these ends may 20 be connected together at any desired time after their formation. It will also be understood that they may be connected together in any suitable manner, of which only two examples are shown, one illustrating the 25 drawn out top and bottom connected together and the other illustrating the drawn out edges connected together.

From the foregoing description, it will be seen that a draft gear yoke or the like 30 produced according to this invention is for all practical purposes seamless (the seam connecting the end portions 18 not being considered as it in no way affects the strength of the yoke). The process is a 35 simple straightforward one and of such nature that it will consolidate the metal and remove flaws or low density spots, which would be points of inherent weakness in the finished article. The process may be carried 40 out quickly and inexpensively without the

use of special tools other than the necessary dies.

Having thus described my invention, what I claim is:—

1. In a process of making draft gear yokes, the step of closing one end of a tube.
2. In a process of making draft gear yokes, the steps of forming tongues at one end of a tubular body open at both ends and uniting said tongues to close one end of the 50 body.
3. In a process of making draft gear yokes, the steps of flattening to rectangular form a length of cylindrical tubing open at both ends, forming jaws on opposite sides 55 of the rectangular body at one end thereof and folding said jaws over the end of the body in a manner to close the same and connecting the folded jaws.

4. A process of making draft gear yokes, 60 which comprises forming jaws at one end of a tubular body, drawing out portions at the opposite end of the body, connecting said drawn out portions together, slotting the jaws and opening opposite sides of the body. 65

5. A method of making draft gear yokes, which comprises flattening to rectangular form a length of cylindrical seamless tubing open at both ends, forming jaws at one 70 end of said body, closing the opposite end of the body, slotting the jaws, and opening diametrically opposite sides of the body.

6. A method according to claim 5, having the additional step of enlarging that end of the body from which the jaws are formed 75 prior to the formation of the jaws.

In witness whereof, I have hereunto set my hand.

ARTHUR J. CANFIELD.
